US00D841032S

(12) **United States Design Patent** (10) **Patent No.:** **US D841,032 S**
(45) **Date of Patent:** **** Feb. 19, 2019**

(54) **DISPLAY SCREEN WITH GRAPHICAL USER INTERFACE FOR LIVE VIDEO SHARING**

(71) Applicant: **Twitter, Inc.**, San Francisco, CA (US)

(72) Inventors: **Tyler Jan Hansen**, San Francisco, CA (US); **Kayvon B. Beykpour**, San Francisco, CA (US); **Joseph Harold Bernstein**, San Francisco, CA (US); **Aaron William Wasserman**, San Francisco, CA (US); **Nils Victor Rocine**, San Francisco, CA (US); **Alexander Kayvon Khoshnevisan**, San Francisco, CA (US); **Geraint John Davies**, Bodorgan (GB)

(73) Assignee: **Twitter, Inc.**, San Francisco, CA (US)

(**) Term: **15 Years**

(21) Appl. No.: **29/589,739**

(22) Filed: **Jan. 4, 2017**

(57) **CLAIM**

The ornamental design for a display screen with graphical user interface for live video sharing, as shown and described.

DESCRIPTION

FIG. 1 is a front view of a first embodiment of a display screen with graphical user interface for live video sharing, showing the new design;

FIG. 2 is a second embodiment thereof;

FIG. 3 is a third embodiment thereof;

FIG. 4 is a fourth embodiment thereof; and,

FIG. 5 is a fifth embodiment thereof.

The broken line showing of the device, display screen and graphical user interface are included for the purpose of illustrating environmental structure and portions of the article and form no part of the claimed design.

1 Claim, 5 Drawing Sheets
